Edward L. Knight

N. PETERS, Photo-Lithographer, Washington, D. C.

UNITED STATES PATENT OFFICE.

BENJAMIN J. PAVYER AND THOMAS BURNS, OF ST. LOUIS, MISSOURI,
ASSIGNORS TO THE ST. LOUIS TYPE FOUNDRY, OF MISSOURI.

PAPER-CUTTING MACHINE.

SPECIFICATION forming part of Letters Patent No. 413,086, dated October 15, 1889.

Application filed December 31, 1888. Serial No. 295,058. (No model.)

To all whom it may concern:

Be it known that we, BENJAMIN J. PAVYER and THOMAS BURNS, both of the city of St. Louis, in the State of Missouri, have invented 5 a certain new and useful Improvement in Paper-Cutting Machines, of which the following is a full, clear, and exact description, reference being had to the accompanying drawings, forming part of this specification.

10 This is an improvement in the clamping-bar; and it consists in the manner of construction by which the clamping-face of the bar may be adjusted in width, as and for the purpose hereinafter set forth.

15 Figure I is a front view of enough of the machine to illustrate our invention. Fig. II is a top view of the same. Fig. III is a transverse section of the machine at III III, Fig. II, with part of the guide-frame broken out, and 20 showing the clamping-bar, &c., in rear elevation, with the movable part of the clamping-bar in its higher position on the body of the clamping-bar. Fig. IV is a transverse section of the machine at the rear of the clamping-bar, showing the movable part of the bar 25 in its lower position. Fig. V is a bottom view of the clamping-bar. Fig. VI is a detail vertical section at VI VI, Fig. III. Fig. VII is a detail vertical section at VII VII, Fig. IV. 30 Fig. VIII is a detail vertical section at VIII VIII, Fig. III. Fig. IX is a detail vertical section of a modification, the section being taken at line VII VII, Fig. IV.

1 is an ordinary or any suitable frame, having a table 2, on which the paper is laid for cutting.

3 is the wooden bar let into the table to receive the impact of the knife, as usual.

4 is the arch-frame, whose uprights 5 have 40 the guides for the knife frame or bar 6.

7 is the knife.

No novelty is claimed in the above parts.

The clamping-bar (to which the invention applies) has a body 8, whose end guide-ribs 9 45 work in guide-grooves 10 of the uprights 5. The bar 8 has a recess 11, occupied by a movable piece or bar 12, whose lower face 13 is adapted to bear upon the pile 14 of paper which is being cut. The piece or bar 12 has 50 at the ends guide-ribs 15, which work in the

grooves 10 below the guide-ribs 9 of the body of the clamping-bar. The piece 12 has a projecting lip or rib 16, which, when the piece 12 is in its lower position, as seen in Fig. VII, enters a rabbet-groove 17 in the side of the 55 main bar or body 8. The purpose of this is to prevent the upward bending of the piece or bar 12 when the pressure is upon the paper 14. The piece 12 has lugs 18 with vertical slots at 19 for the passage of the screw-bolts 60 20, which screw into the body 8. When the piece 12 is in its lower position and these bolts are screwed up tight, the lip 16 is forced into the groove 17 and the lower faces of the body 8 and piece 12 are flush with each other, so 65 as to form a broad surface for bearing on the paper 14. The piece 12 may be fastened in its upper position, as seen in Figs. III and VI, by the screw-bolts, or it may be held up by other means—for instance, by spring-catches 70 21. The spring-catches are attached at the lower ends to the piece 12, and have near the upper ends studs 22, which enter holes 23 in the side of the body or main part 8 of the clamping-bar. (See Figs. III and IV.) The 75 upper ends of the springs are bent outward, so as to give a finger-hold in releasing the studs 22 from the holes 23.

24 is the gage, which is constructed to enter the recess 11 when the piece 12 is in its upper 80 position, so as to render the machine available for cutting the paper into narrow strips, whose width is determined by the gage. (See Fig. VI.) When, however, the paper is cut of greater width, the piece 12 is fixed in its 85 lower position, as seen in Fig. VII, so as to give a broad bearing on the paper.

In the modification shown in Fig. IX the piece 12 extends beneath the lower edge or face 25 of the body 8, so as to form the whole 90 bearing-face when in the lower position. When the narrow face 25 alone is used, the piece 12 is of course elevated, so as to be out of the way of the gage, as before described.

26 is the hand-screw by which the clamp- 95 ing-bar is raised or lowered.

27 is the hand-screw by which the gage is moved longitudinally on the table.

We claim as our invention—

1. The clamping-bar of a paper-cutter, with 100

- the piece 12 movable vertically in a recess 11 of the bar, substantially as and for the purpose set forth.
2. The combination, in a clamping-bar for paper-cutters, of the main part 8, having a recess 11 and a rabbet-groove 17, and the piece 12, movable vertically in such recess and having a rib 16 adapted to occupy the groove 17, substantially as and for the purpose set forth.
- 10 3. The combination, in the clamping-bar of a paper-cutter, of the main part or body 8, having a recess 11, and the piece 12, vertically movable in the recess, having guide-ribs 15 at the ends, and slotted lugs 18, and the screw-bolts 20, substantially as and for the purpose 15 set forth.
4. The combination, in the clamping-bar of a paper-cutter, of the main part 8, with recess 11 and rabbet-groove 17, the piece 12, having a rib 16, slotted lugs 18, and spring-catches 21, and the bolts 20, all substantially as and for the purposes set forth.

BENJAMIN J. PAVYER.
THOMAS BURNS.
